UNITED STATES PATENT OFFICE.

FREDERICK WEINBERG, OF DETROIT, MICHIGAN.

FUEL-FEEDING APPARATUS.

1,242,287.

Specification of Letters Patent.

Patented Oct. 9, 1917.

Application filed December 11, 1914. Serial No. 876,604.

To all whom it may concern:

Be it known that I, FREDERICK WEINBERG, a citizen of the United States, residing at Detroit, county of Wayne, State of Michigan, have invented a certain new and useful Improvement in Fuel-Feeding Apparatus, and declare the following to be a full, clear, and exact description of the same, such as will enable others skilled in the art 10 to which it pertains to make and use the same, reference being had to the accompanying drawings, which form a part of this specification.

My invention relates to apparatus for supplying a hydrocarbon to a current of air to form a combustible mixture and is especially designed to be used with an internal combustion engine.

A special object of my improvements is 20 to provide an improved mode of drawing the liquid hydrocarbon from the supply reservoir and for maintaining a constant level in the reservoir from which the spraying nozzle is directly supplied and an apparatus 25 that shall maintain a constant level relative to said nozzle when such direct supply reservoir is tipped at different angles and means for supplying from said nozzle quantitatively a less proportion of hydrocarbon to 30 the air at high speeds.

I secure this object in the device illustrated in the accompanying drawings in which,

Figure 1, is a cross section of an apparatus 35 embodying my invention together with so much of the supply reservoir and the intake passage of an internal combustion engine as is necessary to illustrate the relative arrangement of said apparatus with reference 40 to these parts.

Fig. 2, is a section similar to Fig. 1 showing a part of said apparatus with the movable parts in a second operative position.

Figs. 3, 4 and 5 are detail sectional views 45 of a part of said apparatus illustrating how a constant level of the liquid in the direct supply reservoir relative to the spraying nozzle is maintained with different angles of lateral inclination of such reservoir.

50 *a a* is a casing constituting an auxiliary tank divided into two compartments forming a constant level reservoir *b* and an intermediate reservoir *c*, the latter being located directly above the former. *f* is a short pipe, or passage, leading from the reservoir *c* and extending a short distance downward

into the reservoir *b*, the lower end of the passage, or pipe, *f* is cut or chamfered to an angle which may be about 45 degrees, as shown, and this lower end is open, the highest part of said opening being indicated by the reference letter *f*.
60

b is a passage putting the upper part of the reservoir *b* into communication with the outer air.
65

The reservoir *c* is normally closed from the atmosphere. If now a liquid, as gasoline is poured into the reservoir *c*, it will flow down the pipe, or passage, *f* until it has filled the reservoir *b* to a level which 70 shall close the opening of the lower end of the passage *f* and prevent air passing up said passage, and this level of liquid in the reservoir *b* will be maintained, or if liquid is removed from it, it will be restored, automatically, by a supply from the reservoir *c* in a familiar and well understood manner. If now the reservoir *b* is turned to different angles, as indicated in Figs. 3, 4 and 5, the level will still be maintained at the 80 height of the point *f*.
75

r is the intake passage through which the air is drawn for the charge for an internal combustion engine.

e indicates a supply tank forming a source 85 of supply of liquid hydrocarbon.

d is a normally air tight float chamber, in the example shown formed within the reservoir *c*. *g*, is a passage through the bottom of the chamber *d*. *h* is an automatic outwardly opening valve adapted to control the passage *g*, and *i* is a pipe communicating with the interior of the chamber *d* and extending downward beneath the level of the liquid in the supply tank *e*.
90

j, is an opening through the top of the chamber *d* and *m* is a second opening by which, when the opening *j* is unobstructed, the chamber *d* will be placed into communication with the reservoir *c* through the openings *j*, *m*. *k* is a valve adapted to control the opening *j*. *3*, is a valve stem extending downward from the valve *k*. *y*, is a double armed lever pivoted to a stationary support *z*. A rod *x* is pivotally connected at its upper end with the outer end of one arm of the lever *y*, the other end 2 of said lever extends between two lugs 12 on the stem 3. *4*, is a spring secured at its ends at opposite sides of the chamber *d* and extending transversely across said chamber. The spring *4* is bent between its secured ends and at its 100 105 110

center is secured a float 5. The spring 4 extends between two lugs 11 on the valve stem 3 and between another pair of lugs on the valve stem p .
 5 n is an opening extending through the top of the chamber d provided with a valve seat at both ends against which the valves p and o are adapted to seat to close the opening n . q , is a pipe opened at one end into the passage r and at the other end into an inclosed chamber with which the passage n communicates.

8, is a throttle valve in the passage r and 9 is a passage leading from beneath the level of the liquid in the chamber b to a point just above the closed valve 8.

10 t is a conical sheet metal sleeve fitting at its ends and adapted to reciprocate in the passage r and being constricted toward its center so as to leave a vacuum chamber between said sleeve and the wall of the passage r and to form a strangling tube. The pipe q communicates with the passage r in said vacuum chamber. v is a coil spring resting at its upper end and against lugs w w^2 and at its lower end pressing the tube t downward. u is a lug limiting the downward travel of the tube t . s is a delivery, or spraying nozzle, leading from the reservoir b and extending into the passage r and terminating in a spraying aperture s^1 in the constricted portion of the tube t .

15 The lugs w w^2 and u are fixed eccentrically to screw threaded plugs which extend through the wall of the passage r . By turning said plugs the position of the lugs is altered and thus the tension of the spring v may be adjusted by means of the lugs w w^2 or the position of the tube t by means of 20 the lug u .

25 The plug from which the lug w^2 extends is provided with a lever arm at its outer end and this arm is united by a connecting rod with the arm 13 by which the throttle valve is manipulated, so that the adjustment of 30 the throttle valve shall also adjust the tension of the spring v .

35 7, is a cock extending from the air space of the reservoir c to the outer air. By opening the cock 7 air may be admitted to the reservoir c and the liquid therein will thereby be permitted to flow through the tube f into the reservoir b to temporarily raise the level of the liquid therein.

40 45 It will be observed that the points f^1 and s^1 are directly in line with each other longitudinally of the vehicle so that when the reservoir is tipped laterally, as shown in Figs. 3, 4 and 5, the points indicated by said letters will remain at the same level as 50 shown.

55 The operation of the above described device is as follows:

60 When there is a sufficient amount of liquid 65 in the reservoir c and chamber d , the float f

will be raised thereby and will press the spring 4 up to and beyond the straight line between its supports when the energy accumulated will carry it positively upward to the position shown in Fig. 2 thus closing the opening n by means of the valve p and raising the valve k through the lugs 11 and valve stem 3 and the raising of this valve stem carries the end 2 of the lever y upward and presses the rod x downward striking against a lug or arm extending from the valve h and assisting to open said valve.

65 In this position it will be noted that both the air spaces and the liquid spaces of the reservoir c and chamber d are in communication with each other and liquid may freely flow from the latter to the former.

70 When the level of the liquid in the reservoir c and chamber d has fallen by reason of the draft of the engine from the reservoir b , the float 5 will fall drawing the spring 4 down thus drawing the valve p from its seat and causing the valve k to close the passage j . The valve h will now automatically close by gravity.

75 In this position of the parts the connections between the air and liquid spaces of the chambers c and d are closed and the draft of the engine will draw the air through the pipe q and past the valve o from the chamber d thus causing a partial vacuum in said reservoir and drawing a supply of liquid fuel from the tank e through the pipe i into the chamber d causing the level of the liquid to rise in said chamber until the parts are returned to the position shown in Fig. 2, when the liquid thus drawn through the pipe i will be free to flow into the reservoir c and from thence through the passage f to the reservoir b . It may be observed that the valve h will open automatically as soon as the passage j is opened by the valve k on account of the higher level in the chamber d and because of the rod x striking against a lug extending from said valve.

80 If the throttle valve 8 is closed or nearly closed, the liquid fuel will be drawn through the passage 9 and the engine may be started or primed by causing the fuel to be delivered through the passage 9.

85 The reference number 20, Fig. 1, indicates a water jacket surrounding the reservoir b and acting to impart heat to said reservoir. This water will be supplied from the jacket 90 of the engine or from a similar source of heat connected with the engine.

90 The chamber between the Venturi tube and the wall of the intake passage will communicate by the passage t^2 with the intake passage and therefore will have a partial vacuum drawn therein which will be somewhat modified by the area of the communicating passage between said chamber and the intake passage.

What I claim is:

1. In an apparatus of the kind described, the combination of a supply tank, a vacuum producing passage, an inclosed chamber 5 having a liquid space and an air space, said vacuum producing passage communicating with said chamber, a conduit extending from a point beneath the liquid in said supply tank to said inclosed chamber, an inclosed intermediate reservoir having an air space and a liquid space, a liquid conducting passage leading from the liquid space of said chamber to said intermediate reservoir, means for permitting the flow of liquid 10 from said chamber to the intermediate reservoir and preventing the flow in the reverse direction, and means closed to the outer air for connecting and disconnecting the air spaces in said chamber and intermediate 15 reservoir.
2. In an apparatus of the kind described, the combination of a supply tank, an inclosed chamber, a vacuum producing passage communicating with the interior of 20 said inclosed chamber, a conduit extending from a point beneath the liquid in said supply tank to said inclosed chamber, an inclosed intermediate reservoir, means whereby the fluid in said chamber is caused to 25 flow to the intermediate reservoir, a constant level reservoir open to the atmosphere, and a passage from the intermediate reservoir to said constant level reservoir open at its 30 lower end and so located that the liquid in 35 said constant level reservoir shall form an air seal so that a substantially constant level shall be thereby maintained in said constant level reservoir.
3. In an apparatus of the kind described, 40 the combination of a supply tank, an inclosed chamber, a vacuum producing passage communicating with the interior of said chamber, a conduit extending from a point beneath the liquid in said supply tank to 45 said chamber, an inclosed intermediate reservoir, means for connecting and disconnecting the upper portions of said chamber and intermediate reservoir whereby the fluid in said chamber is caused to flow by 50 gravity to said intermediate reservoir, a constant level reservoir open to the atmosphere, and a passage leading from said intermediate reservoir to said constant level reservoir open at its lower end and so located that the liquid in said constant level reservoir shall form an air seal so that a substantially constant level shall be thereby maintained in said constant level reservoir.
4. In an apparatus of the kind described, 55 the combination of a supply tank, an inclosed chamber, an intake passage to an internal combustion engine, a passage communicating with the interior of said chamber and said intake passage, a conduit ex- 60 tending from a point beneath the liquid in said supply tank to said chamber, an inclosed intermediate reservoir, means operating when the air pressure in said chamber and intermediate reservoir is equalized for 70 permitting the fluid in said chamber to flow to said intermediate reservoir, a constant level reservoir open to the atmosphere, a passage leading from the intermediate reservoir to said constant level reservoir open at 75 its lower end and so located that the liquid in said constant level reservoir shall form an air seal so that a substantially constant level shall be thereby maintained in said constant level reservoir, and a nozzle extending from 80 said constant level reservoir into said intake passage.
5. In a combination consisting of an intake passage, a liquid reservoir open to the atmosphere, a supply nozzle extending from 85 said reservoir to said intake passage, an inclosed chamber located at a higher level than said reservoir, a passage extending from said chamber downward into said reservoir and open at its lower end and so 90 located that the liquid in said reservoir shall form an air seal so that normally a substantially constant level shall be thereby maintained in said reservoir, and means for opening the air space of said chamber to the 95 outer air to the extent and for the time required.
6. In an apparatus of the kind described, the combination of a supply tank, an intake passage, an inclosed chamber having a 100 liquid space and an air space, a passage communicating with the air space of said chamber and said intake passage, a conduit extending from a point beneath the liquid in said supply tank to said chamber, an inclosed intermediate reservoir, a passage leading from the liquid space of said chamber to said intermediate reservoir, means for permitting the flow of liquid from said chamber to the intermediate reservoir and preventing a flow in the reverse direction, means for equalizing the air pressure in said chamber and intermediate reservoir when required, a constant level reservoir open to the atmosphere, a conduit leading downward from the liquid space in said intermediate reservoir and opening into said constant level reservoir and so located that the liquid in said constant level reservoir shall form an air seal so that a substantially constant level shall be thereby maintained therein, and a supply nozzle extending from 110 said constant level reservoir to said intake passage.
7. In an apparatus of the kind described, 115 the combination of an intake passage, a liquid reservoir open to the atmosphere, a supply nozzle extending from said reservoir to said intake passage, an inclosed chamber located at a higher level than said reser- 120
- 125

- 4
- voir, a passage extending from said chamber downward into said reservoir and open at its lower end and so located that the liquid in said reservoir shall form an air-
5 seal so that a substantially constant level shall be thereby maintained in said reservoir, and a manipulatable valve whereby air may be admitted to said chamber in required volume to prime an engine.
- 10 8. In an apparatus of the kind described, the combination of a supply tank, an intake passage, an inclosed chamber having a liquid space and an air space, a passage communicating with the air space of said chamber and said intake passage, a conduit extending from a point beneath the liquid in said supply tank to said inclosed chamber, an inclosed intermediate reservoir, a passage leading from the liquid space of said chamber to said intermediate reservoir, means for permitting a flow of liquid from said chamber to said intermediate reservoir and preventing a flow in the reverse direction, and means controlled by the quantity of liquid 20 in said chamber for equalizing the air pressure in said chamber and intermediate reservoir when required.
9. In a vacuum feed system, the combination of a liquid supply tank, a vacuum-producing passage, an auxiliary vessel having an upper and a lower chamber, a conduit connecting said tank and auxiliary vessel, a passage communicating with said auxiliary vessel and said vacuum-producing passage, 25 a check valve between the chambers opening

toward the lower chamber, and a float in the upper chamber adapted to operate said valve mechanically.

10. In a vacuum feed system, the combination of a liquid supply tank, a vacuum-producing passage, an auxiliary vessel having an upper and a lower chamber, a conduit connecting said tank and auxiliary vessel, a passage communicating with said auxiliary vessel and said vacuum-producing 40 passage, a check valve between the chambers opening toward the lower chamber, a float in the upper chamber adapted to operate said valve mechanically, said float being adapted to be moved in both directions by 45 the fluid and mechanical means at a variable velocity.

11. In a vacuum feed system, the combination of a supply tank, a vacuum chamber, a conduit leading from said supply tank to 50 said vacuum chamber, means for making and breaking a vacuum in said chamber, an intermediate chamber, a conduit leading from said vacuum chamber to said intermediate chamber, a constant level chamber, a conduit leading from said intermediate chamber to said constant level chamber, the last named conduit being continuously open 60 and uninterrupted.

In testimony whereof, I sign this specification in the presence of two witnesses.

FREDERICK WEINBERG.
